PREFABRICATED METAL INSULATED BUILDINGS

This invention relates to an entire preengineered building structure including integral foundations and natural thermodynamic principles for the efficient dehumidification and cooling of the interior air in buildings. The buildings are comprised entirely of metal components which rely on the natural thermodynamic principles of reflective surfaces to obtain heat insulating barriers far superior to conventional insulating materials.

The thermodynamic principles of the cooling effects caused by the evaporative characteristic of water is utilized to effectively dehumidify and cool exterior and interior air used for building ventilating purposes. The net result of the utilization of these thermodynamic principles achieves economies in initial heating and cooling equipment costs, and further economies are achieved through the years in reduced operating cost as compared to conventional equipment.

The relationship of exterior climatic and/or weather conditions to interior environmental conditions is controlled by a series of thermal bars which react to solar radiation, or electrical energy as the case may be, and govern the natural thermodynamic principles used to achieve desired interior environmental conditions.

Although the building is entirely constructed of aluminum because thermal properties of aluminum are superior to all metals except gold and silver and offer the additional advantage of light weight and minimum maintenance, other metals may be employed in the place of aluminum with knowledge that thermal efficiency will be effected in direct relationship to the thermal properties of the selected metal as compared to aluminum.

OBJECTS AND FEATURES

The principal features and objects of this invention are to produce:

1. A completely integrated preengineered metal building structure wherein functionally, portable foundation systems form an integral part of the building structure, and wherein functionally the building components form an integral part of the heat insulating mediums, and wherein functionally the building components form an integral part of the dehumidification and cooling of building ventilating air;
2. A completely integrated preengineered metal building structure wherein aluminum is used as the sole building and structural material establishing the superior economic value of this metal as compared to other metals and other materials;
3. A completely integrated preengineered metal building structure with foundation systems that permit buildings to be erected on low soil bearing sites where conventional foundation systems would be more costly and impracticable;
4. A completely integrated preengineered metal building structure with foundation systems that can be dismantled and erected on new sites, and which in dismantled form can be transported at greatly reduced shipping costs as compared with conventional structures;
5. A completely integrated preengineered metal building structure with foundation systems wherein all parts are salvageable and interchangeable with other structures of this concept, and are not limited in size, shape, form, design, character, or purpose and may be used, designed, erected, and finished for any requirement that normal or conventional building structures are adapted to or used for;
6. A completely integral preengineered metal building structure with foundation systems that are utilized for water storage, fuel storage, and septic tank facilities, and that uses the water stored in the foundation tanks for an evaporative cooling system or process within the wall and roof structure of the building for the purpose of cooling or heating the building;

7. A completely integral preengineered metal building structure with foundation systems that will dehumidify and cool or heat building air by natural thermodynamic principles, and one that combined with internal building utilities is designed to produce more efficient performance of the natural thermodynamic principles used to dehumidify, cool and/or heat interior building spaces;
8. A completely integral preengineered metal building structure with foundation systems which utilize the thermal expansion or construction of metal bars to control the mechanical devices which select the thermodynamic principle that will achieve the desired interior environmental condition. The thermal bars may be energized by solar radiation or the lack of solar radiation, they may also be energized by auxiliary electrical heating elements and may be arranged in combination for any desired system;
9. A completely integral preengineered metal building structure with foundation systems that apply the thermal properties of reflective surfaces to effectively insulate the building against loss or gain of heat and function as structural components of the building, and one that uses the water stored in the foundation tanks for an evaporative cooling system or process within the wall and roof structure of the building for the purposes of cooling or heating the building;
10. A completely integral preengineered metal building structure with foundation systems that will dehumidify and cool or heat building air more efficiently with the aid of mechanical air handling devices, and one that will dehumidify and cool or heat outside air for building ventilating purposes by natural thermodynamic principles and/or with mechanical air handling devices;
11. A completely integral preengineered metal building structure with foundation systems engineered to collect and store rain water in the foundation tanks to be used for building dehumidification, cooling or heating purposes; and
12. A completely integrated preengineered metal building wherein the condensation of water vapor by the thermodynamic processes is controlled and takes place in a predetermined and controlled manner as to eliminate the detrimental effects of said condensation of the interior surfaces of the building.

SUMMARY

In general this invention relates to an evaporative outer chamber having outer sheathing supported by vertical bents and having water pans between the bents, inner static insulating chamber of preferably honeycomb or similar material between metal reflecting surfaces, and an intermediate dehumidification chamber between the other two. Extruded structural aluminum sections are known as bents. Bents have longitudinal grooves adapted to receive insulation. Honeycomb material is in panels between bents with side stripes shaped to receive bents with insulation therebetween. Vents and dampers are provided for air circulation which are controlled by thermal bars. Foundation of metal drums having bents are secured thereto, and plastic bag liners are inserted through plug holes in the drum ends.

Specifically, according to the present invention the building construction comprises an evaporative cooling chamber, having outer sheathing supported by vertical bents and having inner water pans between the bents, an intermediate dehumidification chamber, and a static insulation chamber having inner and outer metallic reflecting surfaces with porous non-metallic insulating material therebetween. The bents are joined end to end at the roof ridge and form a clear span between the side walls. The bents are structural shape having longitudinal grooves receiving strips of high strength low thermally conductive plastic and shaped to retain the same. The insulating material is formed in panels between the bents, and the panels have metal side strips shaped to receive their

respective bents with low thermal conductivity pliable material therebetween.

FIG. 2 is a section through the basic building structure of a bent formed by an I-beam;

FIG. 3 is an isometric projection of the framing formed by the bents of FIG. 2;

FIG. 4 is an isometric projection of a deformed sheathing (see FIG. 18);

FIG. 5 is a similar view of a modified sheathing, while FIG. 6 is a detail of the joint taken on the line 6-6 of FIG. 5;

FIG. 7 shows the metal water pan;

FIG. 8 shows the construction of the static reflective insulating chamber, while FIGS. 9 and 9A are cross-sectional views taken on the lines 9-9, and 9A-9A, respectively;

FIG. 10 is a diagram of the heating, cooling, dehumidifying and insulating of the building;

FIG. 11 is a vertical section through the bottom of the three cavities shown in FIG. 10; while FIG. 12 is a horizontal section taken on the line 12-12 of FIG. 11.

FIG. 13 is a detail of the roof ridge structure shown broadly in FIG. 10;

FIG. 14 is a diagram similar to FIG. 10 but including lighting fixtures;

FIG. 15 is a detail of the light fixture;

FIG. 16 illustrates how outside air is introduced into the dehumidified chamber, while FIG. 17 is an extension of the eave shown partially in FIG. 16;

FIG. 18 shows a modification in which a structural beam 57 is introduced perpendicular to the bents 29;

FIG. 19 is similar to FIG. 11, but shows the inner cavity interrupted by exterior doors.

FIGS. 20 and 21 illustrate the inner cavity interrupted by the heads and sills, respectively, of the window openings;

FIG. 22 illustrates a basic automatic thermal unit (see FIG. 13), installed in an end wall.

FIGS. 23 and 23A show details of the thermal unit, while FIG. 24 shows the modified form wherein the thermal bar is surrounded by a heating coil;

FIGS. 25-28, including 25A, illustrate details of the thermal operating mechanism;

FIG. 29 shows mechanical fans incorporated into the system and metal ducts to distribute air at predetermined rates.

DESCRIPTION OF PREFERRED EMBODIMENTS

As shown in FIG. 1, the foundation assembly consists of foundation tank cradles resting on the earth. The foundation tanks comprise bottom semicircular metal forms 2 resting in foundation cradles 1 and quarter circular metal forms 3 fastened to the flanges 4 of the bottom semicircular metal forms. T-shaped subfloor purlins 5 form the connecting member between the two quarter segments 3 of the foundation tanks. Subfloor foundation tank cradles 6 frame between the quarter segments 3 of foundation tanks, subfloor purlins 5 and the foundation cradles 1.

Foundation tank plugs 7 are inserted in the end of each assembled foundation tank which does not have structural column bents 8 framing into it. The vertical structural bents 8 bear on the inner surface of the foundation tanks 2 and are held in alignment by and are framed into the semicircular tank plugs 7 and subfloor purlins 5. Walls or structure framing perpendicular 9 to the foundation tanks 2-3 and cradle assembly 6-1 are framed between and into the structural foundation band 10. Vertical structural bent 9 members framing between foundation cradle assemblies 1 and 6 are framed into the foundation band 10 and laterally braced to the foundation tanks 2, 3 by intermediate foundation cradle assemblies 11.

The metal structural subfloor 12 is ribbed sheet metal secured to the subfloor purlins 5 by screws or bolts. The subfloor underlayment 13 is preformed to fit the profile of the structural subfloor 12, this material may vary in substance depending on the use intended for the building. For normal use as a house the substance would most likely be a rigid insulating material fastened to the structural subfloor by mechanical means over which conventional flooring 15 systems, such as lumber, plywood, performed plastic, or concrete, may be laid. For more substantial flooring systems, plywood 16 may be used as subfloor underlayment, extruded plastic 13 conforming to the profile of the structural subfloor may be used as a subfloor. Heavy sheet aluminum 17 may be fastened directly to the structural subfloor where heavy concentrated loads are to be employed. This latter may be finished with conventional flooring.

Foundation tanks are used as storage tanks for water used for cooling purposes, water used for potable purposes, storage for rain water used for cooling purposes, condensation storage tanks, fuel oil storage tanks, septic tanks. Plastic bags 18 are used to line each foundation tank 2 and 3 and are inserted into the foundation tanks during tank assembly. The ends of each plastic bag are fitted with tube openings which are connected to the internal piping system 19 of the building. The plastic foundation tank liners 18 are removable and replaceable by removing the foundation tank plugs 7, removing the plastic bag 18 and inserting a new plastic bag and replacing the tank plugs 7.

As shown in FIG. 2, the basic building structure employs bents formed by extruded metal I-beams preferably of aluminum. The exterior side of the outer face of the flange is extended perpendicular to the face of the flange to form a continuous riglet 20A along the face of the flange 20 for the purpose of forming a cavity to contain a continuous strip of high tensile strength, low thermal conductivity plastic 21. By the shape of the continuous riglet the plastic is restrained from being pulled out of the riglet thereby forming an integral part of the structural member. The plastic insert functions as an insulator between the main metal structural member 8 and the metal building components that are attached to this structural member thereby reducing the rate of heat transmission between component parts and the structural member 8. The shape and physical character of the plastic insert is designed to achieve the transfer of all structural forces created by building live and dead loads directly to the main structural member 8.

The inner side of the outer face of the flange is extended perpendicular to the face of the flange to form a continuous riglet along the face of the flange 20 for the purpose of forming a cavity to contain a continuous strip of low thermal conductivity plastic 23. By the shape of the cavity the plastic filler is restrained from being pulled out of the cavity, thereby forming an integral part of the structural member. The plastic filler contains a continuous riglet 24 shaped to the form as shown in FIG. 2 of the drawing. The object of this riglet 24 is to form a continuous female compressive receptacle to hold and restrain the edges of the static reflective insulating chamber (see FIGS. 8-9A). The complete structural assembly as hereinbefore described shall be referred to as the structural bent as hereinafter described.

As shown in FIG. 3, the side walls of the building consist of structural bents 8 placed vertically on a module as set by the physical size of the building and climatic conditions which affect the live loads the building structure must sustain. The roof structural bent 29 members frame from the ridge beam 25 to the vertical structural bents 8 and are secured to each other by the use of plates 26 and angles 27 bolted to each member to form a structural joint designed to sustain, transmit and resist all forces created by the combined live and dead loads of the structure. As may be required in the course of erection diagonal tie rods 28 are inserted at selected bays for the purpose of alignment of structure after erection.

The end walls of the building consist of structural bents 9 placed vertically from the base of the building and connected

to the roof structural bents 29 by means of structural angle 27 connections. The vertical bents 8, 9 terminate on the foundation sill 30 for conventional foundations and are anchored to such sill by means of metal angles 27 bolted to the bent and secured to the sill anchor bolts which are imbedded in concrete foundation walls or as hereinbefore described for metal foundations.

The outer sheathing of the building consists of deformed structural sheet metal 31 shown in FIG. 4, or deformed structural sheet metal forms 32 shown in FIG. 5. This sheathing is preferably of aluminum secured to the bents at each deformation 31A or flange 32A by metal screws driven into the plastic inserts 21 of the structural bents 8 and 9. This sheathing transmits the building live loads to the bents and encloses the building. As further shown in FIG. 6 the screws may be concealed from view by clip mouldings 32B which contain weather seals 32C.

As shown in FIG. 7 (and FIGS. 11, 13 and 17), the metal water pan 33 preferably of aluminum runs longitudinally to the structural bents 8, 9 from the base of the building to the roof ridge or roof rafters as in the case of the end wall condition. The metal water pan 33 is attached to the plastic inserts 21 of the structural bents 8, 9 by metal screws and forms the watertight surface which permits and confines the cooling water from the water trough 44 to run from the roof ridge to base reservoir 47 (see FIG. 11).

As shown in FIGS. 8, 9, and 9A (see also FIG. 16) the outer surface 34 of the static reflective insulating chamber encloses the inner surface of the building as formed by the structural bents 8, 9 and inner surface 35 of the static reflective insulating chamber forms the surface of the dehumidification chamber and runs longitudinal to the structural bents 8, 9 from the roof ridge or to the roof rafters in the end wall to the base of the building. The inner and outer metal surfaces of static reflective insulating chamber are held apart by a low thermal conductance honeycomb material 36 which is adhered to the metal surface by an adhesive. Obviously, any other material having a low thermal capacity may be used for insulating purposes.

The edges of the static reflective insulating chamber which are parallel to plane of the bent are formed by a structural metal edge 37, preshaped to receive the edges of the inner surface 35 of this chamber in a riglet 40. The thin metal sheet is retained in this riglet by a low thermal pliable material 38 which separates the chamber from the bent and forms an airtight seal to the dehumidification chamber. The outer surface of this chamber 34 returns around the deformation on the outer leg of the metal edge 37 thereby sealing the chamber along this side and this detail will be referred to as the side insert. The ends of the static reflective insulating chamber, as shown in FIGS. 9 and 10, are sealed with a structural metal edge 39 preshaped to receive the inner surface of this chamber in a riglet 40. The thin metal sheet 35 is retained in this riglet 40 by a low thermal pliable material 38 which separates the chamber from abutting chambers or adjoining surfaces and the preshaped male 39 and female 39 interlocking joint provides a positive seal between panels.

The basic thermodynamic principles of heating, cooling, dehumidifying and insulating the building structure are set in three distinct cavities which are built into the building structure and thermodynamically function or perform under certain climatic and/or weather conditions selectively, collectively, manually or automatically as the case may be.

As shown in FIG. 10, the three cavities are the exterior cavity forming the evaporative cooling chamber, the inner cavity forming the dehumidification and cooling chamber, and the interior cavity forming the static reflective insulating chamber.

As shown in FIG. 10, the profile of the building may be a simple gable roof or have the roof extended upward and out from the roof eave. The exterior cavity in the case of a simple gable roof extends from the base of the building to the roof ridge. As also shown in FIG. 10 the exterior cavity extends

from the base of the building to the window sill and from the window head to the under side of the eave or overhang. The exterior cavity may also extend from a roof valley to the ridge, or the fascia of a roof overhang.

The exterior cavity is formed by the exterior metal sheathing and the water pan and is bounded by the structural bents 8 and 9. The component parts of this cavity are the vents located at the base of the building 41 (see FIG. 11), at the roof ridge 42 (FIG. 12), at the window sills (FIG. 21), at the head of the windows (FIG. 20), at the head of doors (FIG. 19), in the roof valleys (FIG. 16), at the fascias of roof overhangs (FIG. 17), and at the end wall (FIG. 22). The shape and/or configuration of the sidewalls and roof of the building do not affect the application of thermodynamic principles.

When all the vents 41 and 42 of the exterior cavity are in a closed position the cavity functions as a static reflective insulating chamber. The exterior cavity functions as an evaporative cooling chamber when the vents 41 and 42 are moved to the open position and water flows over the water pan 33 from the water trough 44 located at the highest point in the cavity. The excess water is collected in the water trough 47 at the lowest point of the cavity and is drained to the storage tanks. The exterior cavity receives its water supply from a main water supply pipe 84 located at the highest point in the cavity, the flow of water from this pipe 84 and the movement of the vents 41 and 42 are thermostatically controlled by thermal linkage 64 from a thermal bar 60. The function and operation of the thermal control of the cavity will be hereinafter described.

The exterior cavity functions as an evaporative cooling chamber when the air intake vent 41, located at the base and air exhaust vent 42 located at the ridge of the building are moved to the open position by the thermal linkage 64 and water flows over the water pan 33 from the holes 45 in the water trough 44. Exterior air 48 (FIG. 11) enters the exterior cavity through the vents at the base of the building through the vent, this air is heated by conduction with the exterior metal sheathing 31 which has gained its heat from solar radiation.

The air rises in the cavity by convection, passes over the wet surface of the water pan 33 and evaporates the water from the surface of the water pan 33. This evaporative process cools the surface of the water pan to a temperature approaching the wet bulb temperature of a cyclometer. The air continues this thermodynamic process until it reaches the vent 42 located (FIG. 13) at the roof ridges and then it is exhausted into the atmosphere (48A).

The inner cavity is formed by the surface of the water pan 33 and the surface of the static insulating chamber 35 and is bounded on each side by the structural bents 8, 9, and 29. The inner cavity extends from the base of the building to the roof ridge. The extremities of this chamber are open to the interior of the building and chamber may be closed off from the interior of the building by the thermostatically operated dampers 52, 53 located at the roof ridge (FIG. 13) and the base of the building (FIG. 11). The condensation pan 54 located at base of this chamber is connected to the base reservoir 47 by means of a plastic tube trap 59 which seals off the chambers and permits condensation to drain from the chamber.

When the dampers 53, 54 are in a closed position a relatively motionless body of air entrapped in the chamber and the chamber functions as a static reflective insulating chamber. When the exterior cavity functions as an evaporative cooling

chamber the inner cavity will function as a dehumidification and cooling chamber. The dampers located at the ridge 53 and base 52 of the chamber are moved to the open position by the thermal linkage 64 permitting complete air communication between the chamber and the interior of the building.

Natural thermodynamic principles cause warm building air 49 rise to the roof ridge and enter the dehumidification chamber through the vent 53 located at the ridge. As the air enters this chamber it comes in contact with the cooled surface of the water pan 33 and the air is cooled by conduction. As the air is cooled the water vapor in the air is deposited on

the cooled surface of the water pan 33 in the form of condensation. The cooled and dehumidified air 49A will flow through the chamber by convection and leave the chamber through the vent 52 at the base of the chamber. Water deposited on the surface of this chamber will drain to the condensation trough 54, 54A, at the base of the cavity and be drained to the base reservoir 47 and then to the water storage tanks.

As shown in FIGS. 14 and 15, dehumidified cool air 49A is discharged through the vents 52 at the base of exterior walls and circulates within the room area by convection absorbing heat and moisture from surrounding objects and people. The air 49 will rise to the ceiling as it continues to absorb heat and moisture. The lighting fixtures 50 located in the ceiling have openings 51 around the perimeter of the fixture for the purpose of permitting air to enter the fixture, circulate around the perimeter of the light bulb and absorb additional heat from this heat source. The top of the light fixture has openings or vents 54 which permit this heated air to pass from the light fixture to the ceiling plenum by convection. The air will continue to rise in ceiling plenum to the uppermost portion of this space wherein the dehumidification chamber intake vents 53 are located. The air will enter the intake vents by convection and thermodynamic processes of dehumidification and cooling take place as hereinbefore described.

As shown in FIG. 10 the extension of the roof outward from the eaves to form an overhang forms an intersection of the two inner cavities as further detailed in FIGS. 16 and 17. The intersection of the overhang inner cavity permits outside air 49B (FIG. 17) to be dehumidified and mixed with the dehumidified interior building air 49A by means of the modulating damper 56. A further modification of the inner cavity would discharge dehumidified building air through the vent at the eave 52 and the modulating valve 56 would permit complete dehumidified fresh air to be discharged into the building through the vents 52 at the base of the building or at window heads as shown.

As shown in FIG. 18 a structural beam 57 may be introduced perpendicular to the bents 29 in the case of intermediate structural members are required to support the bents in long span buildings. The inner cavity is interrupted by this superimposed beam and vents 52 and 53 are introduced each side of said beam for the purpose of creating more than one cavity to function as hereinbefore described.

As shown in FIG. 19 the inner cavity is interrupted by exterior doors. Vents 52 are installed at the head of each door 58 to discharge dehumidified air into the room and functions as hereinbefore described.

As shown in FIGS. 20 and 21 the inner cavity is interrupted by the heads (FIG. 20) and sills (FIG. 21) of window openings. Vents 52 are installed at the head of each window which will permit dehumidified cooled air to flow over the surface of the window 59 and absorb the heat from the window. The condensation troughs 52 drain the condensation from the window head to the window sill cavity by means of plastic tubes installed along the window jamb.

As shown in FIG. 21 the inner cavity begins again at the window sill by the sill vent 53 and terminates at the building base as in FIG. 11. Air will enter this inner cavity through the sill vent 53 and be discharged into the room through the base vents 52 and the cavity functions as hereinbefore described.

Referring again to FIG. 10, water used for cooling purposes may be used for heating purposes within the limits of temperature differential between exterior air temperature and interior air temperature. The water used for cooling purposes that is stored in the foundation storage tanks would have a temperature near that of the average wet bulb temperature for a period preceding the period when the heating cycle would be required.

For the purposes of illustration assume the average wet bulb temperature for the preceding period was 70°F., then the water in the foundation storage tanks would be approximately 70°F. Assume the outside air temperature is 40°F. with an indoor temperature of 60°F. and it is desired to maintain an in-

door temperature of 68°F.; the water in the storage tanks is pumped up to the water trough 44 at the roof ridge and allowed to run over the surface of the water pan 33 with the exterior vents 42 and 41 of the evaporative cooling chamber in a closed position. The metal surface of the water pan will reach the temperature of the storage tank water (70°F.). The vents 53 and 52 in the dehumidification chamber are in the open position.

The air in contact with warmed surface of water pan will rise in the chamber by convection drawing room air into the chamber through vents 52, as the air continues to rise in the chamber it will reach the temperature of the water pan and will be discharged into the building through the vents 53 at the top of the chamber located at the ridge roof. The warm air will mix with existing room air and the constant intake of room air into the dehumidification chamber creates a complete cycle of thermal air currents. When the temperature of room air equals the temperature of the water in the foundation storage tanks the heating cycle is complete; water supply is shut off and all vents are moved into a closed position and the building wall and roof system function as a reflective static insulating system.

To obtain complete and automatic environmental control of interior building air treatment solar radiation (or the lack of solar radiation) is utilized to control the natural thermodynamic processes of dehumidifying interior building air all as hereinbefore set forth.

As hereinbefore described for thermodynamic processes for dehumidification and/or heating building air the following application of control devices and/or sequences are applicable but not necessarily limiting any or all collectively, selectively or multiples of the basic technique. The application of the basic thermal control unit (FIG. 22) would function in its entirety under certain climatic conditions and would perform as required for complete and automatic environmental control of interior building air also, the modification of the basic thermal control unit (FIG. 24) would function in its entirety under certain climatic conditions and would perform as required for complete and automatic environmental control of interior building air. Collectively or selectively it is the intention to utilize the basic thermal bar modified to perform the desired mechanical action.

As shown in FIGS. 23 and 23A the basic thermal bar 60 consists of a bar of material with a high thermal coefficient lineal expansion. The thermal bar 60 is held in position and alignment by bolts or screws attached to a mounting bracket 61. The free end of the thermal bar 60 contains a wedge-shaped thermal lever 62 which is adjustable by a retaining bracket, set screw and lock nut assembly 63. To achieve the force of thermal expansion and magnify the lineal expansion of the thermal bar a series of levers and fulcrums is arranged to achieve the desired lineal movement. Each thermal linkage 64 has the thermal force applied by means of wedge-shaped levers close to the lever fulcrum 65. Each thermal link 64 has its fulcrum 65 retained in a fulcrum bracket 66 which is secured to a mounting bracket. As solar radiation heats the thermal bar 60 the thermal bar will expand and its elongation will be in direct proportion to temperature rise of the metal. The thermal lever 62 will move forcing the thermal linkage 64 to rotate on the fulcrum 65 thereby translating the thermal expansion of the thermal bar 60 into rotational movement of the thermal linkage 64. The thermal bar 60 and thermal linkage 64 will reverse its direction of movement in the absence of solar radiation due to the contraction of the metal due to loss of heat or decrease in temperature.

As shown in FIG. 24 the basic thermal bar 60 is modified to include a heating coil 67 surrounding the thermal bar 60. This auxiliary heating element when energized by electrical current will heat the thermal bar 60 and produce the lineal expansion required to activate the thermal linkage, as hereinbefore described.

As shown in FIG. 13 the thermal bar 60 is applied to a combination of thermal linkage 64 to activate the evaporative

cooling chamber exhaust air vent 42 and the cooling and heating valve simultaneously as hereinbefore described.

As shown in FIG. 13 the thermal bar 60 with heating coil 67 is shown applied to the interior vents of the dehumidified chamber.

As shown in FIG. 25 the thermostatically controlled cooling and heating valve assembly consists of the thermal bar 60, thermal linkage 64, thermal setting screw calibrated for temperature control 68, heating valve spring retainer 69, heating valve spring 70, heating valve bushing 71, heating valve packing 72, heating valve 73, heating valve seat 74, heating valve orifice 75, cooling valve 76, cooling valve seat 77, cooling valve spring retainer 78, cooling valve spring 79, valve and spring retainer nut 80, cooling valve packing 81, valve assembly fitting 82, heating and cooling water discharge orifice 83.

As shown in FIG. 26 the thermostatically controlled cooling and heating valve may be connected to the main water supply pipe 84 so as to supply up to four evaporative cooling chambers from the same pipe fitting when water flows through the main supply pipe 84 and temperature conditions do not call for cooling or heating cycles the valve will remain in a closed position and water will bypass the valve orifices.

As shown in FIG. 27 the thermal bar 60 has expanded and moved the thermal linkage 64 into the cooling cycle; as the linkage continues to move it engages the thermal setting screw 68 the force of the movement due to engagement of the thermal setting screw 68 and the thermal linkage 64 force is transmitted to the heating spring valve retainer 69 thence to the heating valve 73 thence to the heating valve seat 74 which in turn will move the cooling valve 76 from its seat 77 allowing cooling water to flow from the main orifice into the heating and cooling discharge orifice 83 and thence into the water trough 44.

The movement of the cooling valve 76 from its seat 77 transferred the force of the thermal linkage to the cooling valve spring retainer 78 and this force is stored in the form of potential energy in the cooling valve spring 79.

When the cooling cycle is complete by the contraction of the thermal bar 60 the thermal linkage 64 will move in the opposite direction and remove the force from the thermal setting screw 68 and the potential energy of the cooling valve spring 79 will force the cooling valve 76 to reseat itself onto the cooling valve seat 77 and the flow of water to the evaporative cooling chamber is stopped. As the thermal bar 60 continues to contract the thermal linkage 64 will pass through the temperature range from the cooling cycle to the heating cycle.

As shown in FIG. 28 the thermal bar 60 has contracted and brought the thermal linkage in contact with the heating spring retainer 69. As the thermal linkage 64 moves in contact with the heating spring retainer 69 the force of the thermal linkage 64 is stored in the form of potential energy in the compression of the heating spring 70 as the heating valve 73 moves away from the heating valve seat 74 heating water will flow from the main orifice around the heating valve 73 to the heating valve orifice 75 and thence to the heating and cooling discharge orifice 83. When the water heating cycle has been completed and supplemental heating is required for interior environmental control the water supply is shut off, the thermal bar 60 will maintain the heating valve 73 in the open position permitting the water to drain from the main water supply pipe to prevent damage to the valve assembly and pipes in the event freezing temperatures should prevail. When the thermal bar 60 expands the thermal linkage will move away from the heating valve spring retainer 69. The potential energy stored in the compressed heating valve spring 70 will reseat the heating valve 73 in the heating valve seat 74.

As shown in FIG. 29, to increase the efficiency of air movement through the dehumidification and evaporative cooling chambers mechanical air handling fans may be incorporated into the system with the aid of additional metal ducts to distribute the air into these chambers at predetermined rates. The addition of this mechanical system does not affect the

thermodynamic principles embodied in this concept but only increases the rate of air movement providing the added advantage of greater rates of cooling and dehumidifying building air.

- 5 The duct system required to achieve a desired thermodynamic performance in the dehumidification chamber will consist of a metal exhaust duct 86 open to each interior room or space and connected to the inlet side of the exhaust fan 85. The mechanical fan will exhaust the air from the interior rooms and force this air through the supply duct 87 connecting the openings 53 to the dehumidification chamber along the roof ridge. The connection from the supply duct to the dehumidification chamber contains adjustable dampers to adjust the amount of air to be delivered to the dehumidification chamber. The air 49 enters the chamber from the duct and is thermodynamically processed as hereinbefore described and is discharged 49A into the rooms or interior spaces through the discharge vents 52 at the base of the building.

FORCED AIR CIRCULATION THROUGH EVAPORATIVE COOLING CHAMBER

An object of this modification is to achieve controlled efficiency of the thermodynamic processes as hereinbefore described with the aid of mechanical air hereinbefore described handling fan and a network of metal ducts to convey this air from the evaporative cooling chamber to the mechanical fan 88 and then exhaust this air to the atmosphere. All exhaust vents 42 of the evaporative cooling chamber as hereinbefore-described and located are connected to a central metal exhaust duct 89 located at the roof ridge. Adjustable dampers regulate the amount of air to be drawn from each chamber and by negative atmospheric pressure created at the inlet side of the fan 88. Air 48A from each chamber is conveyed through the exhaust duct to the inlet side of the fan 88 and is then exhausted to the atmosphere.

40 DEHUMIDIFICATION AND COOLING OF EXTERIOR FRESH AIR

An object of this modification is to dehumidify and cool exterior fresh air 49B prior to admitting this air to the building for ventilating purposes. The mechanical air handling fan 85 is connected by means of a metal duct 87 to the inlet side of the dehumidification chamber located along the roof ridge as hereinbefore described. The inlet side of the mechanical air handling fan 85 is connected by means of a metal duct 90 to the exterior atmosphere. Air 49B is drawn by the fan from the exterior atmosphere and forced into the main supply duct 87 and distributed to each dehumidification chamber wherein the thermodynamic principles as hereinbefore described dehumidify and cool the air before discharging the air 49A through the vents 52 at the base of the dehumidification chamber.

The invention is not to be limited to the precise details disclosed, but instead embraces such embodiments of the broad idea as fall within the scope of the subjoined claims.

The elimination if, or the control of, condensation is a major factor in this invention. The intermediate chamber is designed specifically to predetermine and control where and how condensation takes place.

I claim:

- 65 1. Building construction comprising:
a foundation having vertical bents extending upward therefrom;
surfaces supported by said bents defining successive exterior, intermediate, and interior chambers enclosing the interior of the building;
said exterior chamber having outer sheathing and an inner water supporting surface and having vents for communicating with the atmosphere;
said interior chamber having inner and outer surfaces with porous nonmetallic insulating material therebetween;

said intermediate chamber being formed by the inside of said water supporting surface and the adjacent outer surface of said insulating chamber; and the extremities of this intermediate chamber being open to the interior of the building.

2. Building construction as claimed in claim 1, having means for supplying water to the upper portion of said exterior chamber to flow onto said water supporting surface.

3. Building construction as claimed in claim 1, in which said exterior chamber has outer sheathing supported by said vertical bents, and inner water pans between the bents, and said intermediate chamber being designed specifically to predetermine and control where and how condensation takes place.

4. Building construction as claimed in claim 2, in which said insulating chamber surfaces are reflecting metallic surfaces, and said intermediate chamber being designed specifically to predetermine and control where and how condensation takes place, whereby the control or elimination of condensation occurs.

5. Building construction as claimed in claim 2, having a roof ridge and side walls in which said bents are joined end to end and form a clear span between said side walls.

6. Building construction as claimed in claim 5, in which said bents are metallic structural shapes having longitudinal grooves receiving a strip of high strength, low thermal conductivity plastic and shaped to retain the same.

7. Building construction as claimed in claim 4, in which said insulation chamber is formed by panels between said bents,

said panels having thin metal side strips shaped to receive the respective edges of said metal reflective surfaces.

8. Building construction as claimed in claim 7, in which said thin metal side strips are shaped to receive their respective bents with low thermal conductivity pliable material therebetween.

9. Building construction as claimed in claim 1, in combination with a foundation comprising metal tanks, with said vertical bents bearing on said tanks.

10. Building construction as claimed in claim 9, in which said tanks are drums having heads, said foundation comprises cradles for said drums, and the lower portions of said bents are secured to said cradles and to the heads of said drums.

11. Building construction as claimed in claim 10, in which said tanks contain water to be supplied to said water supporting surface.

12. Building construction as claimed in claim 2, in which thermal elements are operatively connected to closures at said vents permitting atmospheric air to enter into and pass through said intermediate chamber.

13. Building construction as claimed in claim 12, wherein said thermal elements are temperature sensitive and automatically operate by a temperature change in the atmosphere.

14. Building construction as claimed in claim 13, wherein said temperature sensitive thermal element is a thermal bar surrounded by a heating coil and connected to a door closure through a series of connected levers.
